(57) **CLAIM**

The ornamental design for fishing reel portion, as shown and described.

DESCRIPTION

FIG. 1 is a first perspective view of a fishing reel portion in accordance with my new design;
FIG. 2 is a second perspective view of the fishing reel portion illustrated in FIG. 1;

FIG. 3 is a first end elevational view of the fishing reel portion illustrated in FIG. 1;

FIG. 4 is a second end elevational view of the fishing reel portion illustrated in FIG. 1;

FIG. 5 is a top plan view of the fishing reel portion illustrated in FIG. 1;

FIG. 6 is a bottom plan view of the fishing reel portion illustrated in FIG. 1;

FIG. 7 is a first side elevational view of the fishing reel portion illustrated in FIG. 1;

FIG. 8 is a second side elevational view of the fishing reel portion illustrated in FIG. 1; and,

FIG. 9 is a top plan view, similar to FIG. 5, of an alternate fishing reel portion, which is identical to the fishing reel portion illustrated in FIGS. 1 to 8, except that a boundary of the alternate fishing reel portion is shown in broken lines.

In the alternate fishing reel portion illustrated in FIG. 9, the boundary does not form part of the claimed design. In other words, with respect to the alternate design of the fishing reel portion illustrated in FIG. 9, it should be understood that the claimed design extends to the boundary but does not include the boundary shown in broken lines.

The broken line illustration of the environmental structure of a fishing reel in the drawings that is used with the claimed fishing reel portion is not part of the claimed design.
